UNITED STATES PATENT OFFICE

CHARLES R. SELTZER, OF LONGMEADOW, MASSACHUSETTS

PORTABLE DISPLAY RACK

Application filed October 31, 1928. Serial No. 316,249.

This invention relates to improvements in portable display racks. It is particularly designed for displaying oils and polishes which are put up in containers as cans and bottles 5 that are largely used in automobile or filling stations.

An object of the invention is to support a large number of cans or other containers of oils and polishes of different shapes on a 10 portable truck construction, whereby the entire display of the oils and polishes may be moved readily from place to place about a garage or other establishment.

Broadly, it comprises a one piece frame 15 structure to which are pivotally supported a plurality of shelves that are fitted to swing and always assume a vertical position, whereby the containers are properly displayed. Means is provided for quickly attaching and 20 removing these swinging shelves. Means is provided for varying the width of the shelves, so that containers of different sizes may be inserted and frictionally retained in place. Suitable wheels are attached to the supporting 25 frame. The construction and arrangement of the frame is such that normally it is supported in a rearwardly inclined position, but when it is moved on the wheels of the truck, it is tipped rearwardly, which operation 30 permits the shelves to swing into a new position. A further object is to provide removable racks on a fixed lower shelf for receiving containers of different sizes and shapes as rectangular or circular. These and 35 other objects will appear in the body of the specification and the claims.

Referring to the drawings:

Fig. 1 is a side elevational view showing the supporting wheels, the swinging shelves 40 with the containers of different sizes thereon.

Fig. 2 is a front elevational view looking from the right of Fig. 1.

Figs. 3 and 4 are enlarged detailed views showing the key hole joint construction for 45 installing and removing the shelves.

Fig. 5 is an enlarged detail view of one of the swinging metal shelves illustrating the manner of bending the front and rear sides thereof inward for accommodating containers of different sizes.

Fig. 6 is a detailed view of the fixed lower shelf and illustrating one of the removable racks thereon.

Fig. 7 is a removable rack showing rectangular shaped openings for receiving cans 55 or containers of different sizes.

Fig. 8 is a wire rack construction for the same purpose.

Fig. 9 is a top plan view of a removable rack for receiving circular shaped containers, and 60

Fig. 10 is a sectional view on line 10—10 of Fig. 9.

Referring to the drawings in detail:

The main supporting frame is a one piece 65 metal member bent into the form of the letter U, inverted, having the side portions 1 and 2 and the connecting upper portion 3. The bottoms or lower ends of the portions 1 and 2 are bent inward, as shown at 4 and 70 5, which provide a foot or support for the rack. Secured to the opposite sides, 1 and 2, of the main frame are the bars, 6 and 7, by means of the rivets 8. These bars are connected together by means of the rivet 6'. 75 An axle 9, on which are supported the wheels 10 and 11 is located near the lower ends of the bars 6. The side bars 1 and 2 of the frame are formed with key hole shaped openings 80 having the upper enlarged part 13 and the smaller or receiving part 14. The opening 13 receives the head 15 of the rivets 16, the inner heads 16' being attached to the vertical portions or arms 17 of the swinging shelves 18, 19, 20, 21. The bottom of these 85 shelves is indicated at 22, and the bent inward front and rear sides are indicated at 23 and 24. 25 are slits which extend downwardly from the upper edges 26. This slit construction permits the front and rear sides to be 90 folded or bent inward, as shown in enlarged view of Fig. 5, whereby the space 27 may be varied to fit the container or can 28, shown in this figure in dotted lines and thus frictionally retain it in place. The upper edges 95 of the sides 23 and 24 are bent or folded inward indicated at 29, whereby a smooth inner surface of the shelves is obtained. It is obvious that containers of different sizes, as shown in Fig. 1 may be supported. The 100

different shelves are attached to the side bars 1 and 2 by inserting the rivet heads 15 in the openings 13 and then allowing the rivets 16 to enter the smaller openings 14, whereby a pivotal connection of the shelves is obtained with the supporting framework and prevented against accidental removal.

Referring to the bottom shelf 30, an enlarged view of which is shown in Fig. 6, the back of the shelf is indicated at 31, the bottom at 32 and the bent in front wall or side at 33, the upper edge of which is folded over at 34. The ends 35 are fixedly secured to the side frame 1 and 2 by means of the rivets 36. Located on this fixed shelf are the removable rack members, shown in detail in Figs. 7, 8, and 9. The rack member, shown in Fig. 7, comprises a plurality of rectangular shaped openings 37 of different sizes. These openings are formed by the longitudinal and cross plates 38 and 39, which are secured together in any suitable way, as by electrical welding. The openings 37 are not closed at the bottoms. Fig. 6 shows this form of rack in place. Fig. 8 is a wire rack having different sized openings 40 and 41. This rack is provided with the supporting legs 42 on the bottom shelf 30. Fig. 9 shows a further modification of the removable rack which comprises a metal stamping with the top portion 43 and the flanges 44. The upper part 43 is formed with circular openings 45 and 46 of different sizes to receive circular containers of different sizes. The display rack, when in use, is shown in Fig. 1. The foot portions 4 and 5 are supported in front of the wheels 11, on the floor. The center of gravity is understood to fall within the space indicated by the distance between the point 47 of the wheel and the foot portions 4 and 5, whereby the rack is in stable equilibrium, when in use. The operator in moving the display rack from one point to another simply tilts the rack on the axle 9 and then it may be wheeled from one place to another. At the same time, the swinging shelves will assume a vertical position. The different size containers are indicated at 48, 49, 50, 51 and 52.

What I claim is:

1. A display rack for the purpose described comprising a shelf member formed of sheet metal, the opposite side portions of which are bent inwardly in an inclined position toward each other to provide a resilient pinching effect on an inserted article as a bottle for retaining the same in the rack, the end portions of the rack extending upwardly from its bottom portion and means, as rivet pins, secured in the upwardly extending end portions for pivotally supporting the shelf member on a frame member, whereby the shelf will always assume a vertical depending position.

2. A display rack for exhibiting oils and greases in containers comprising inclined side members, a shelf fixedly secured to the side

members, a removable rack located on the fixed shelf, said rack being formed with openings of different sizes for receiving said containers of different sizes, a plurality of swinging shelves having inclined sides and rotatably and removably mounted in the side members.

3. A wheeled supported display rack having, in combination, a supporting frame with opposite side portions; a shelf fixedly secured to the side portions at their lower ends; a removable rack on the fixed shelf, the front side of the shelf being bent inward against the removable rack to retain the rack in place, said rack having different sized openings to receive containers of different sizes.

4. A metal shelf for the purpose described having inwardly bent front and rear resilient side walls for frictionally retaining a container as a bottle in place, the ends of the shelf extending upwardly; pivot pins in the ends for supporting the shelves on a support, as described.

CHARLES R. SELTZER.
